Application March 28, 1945, Serial No. 585,263

12 Claims. (Cl. 64—25)

1

This invention relates to couplings and more particularly to means for connecting two rotating parts, such as parts of an internal combustion engine ignition system, so that automatic angular adjustments of said parts may be effected during rotation thereof, whereby the timing of the sparks produced by the ignition system in the engine cylinders may be automatically varied.

One of the objects of the present invention is to provide novel apparatus for mechanically coupling two rotating elements to each other while permitting of angular adjustment of one of said elements relative to the other.

Another object of the invention is to provide a novel automatic variable coupling for rotating parts which functions in accordance with the speed of rotation of said parts.

A further object is to provide novel means for automatically effecting adjustments in the timing of the ignition system of an internal combustion engine.

Still another object is to provide novel coupling means of the above character whereby two rotating parts may be automatically angularly adjusted in one direction relative to each other at one speed of rotation and in the other direction at a higher speed of rotation.

A still further object is to provide a novel, centrifugally responsive device for effecting an automatic variable connection between two rotatable parts.

Another object is to provide novel means adapted for use in the ignition system of an internal combustion engine for effecting spark advance at one engine speed and a retardation of the spark at a higher engine speed or vice versa.

Another object is to provide a novel ignition apparatus for an internal combustion engine whereby the sparks in the cylinders of the engine may be both advanced and retarded relative to the position of the pistons in said cylinders by a single, centrifugally actuated unit for coupling two rotating parts which are adapted for relative angular movement.

Another object is to provide coupling means of the above character which also functions to some extent as a flexible coupling to avoid damage which might otherwise be occasioned by sudden shocks and quick changes of speed.

The above and further objects and novel features of the invention will more fully appear from the following detailed description when the same is read in connection with the accompanying drawings. It is to be expressly understood, how-

ever, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a fragmentary vertical longitudinal section of a magneto or the like embodying one form of the novel coupling unit comprehended by the present invention;

Fig. 2 is a transverse section on the line 2—2 of Fig. 1;

Fig. 3 is a transverse section on the line 3—3 of Fig. 1; and

Fig. 4 is a top plan view of the centrifugally responsive weight members and intermediate supporting member therefor, shown in Figs. 1 to 3.

Referring to the drawings, the present invention is herein illustrated, by way of example, in the form of a coupling unit adapted for use in the ignition system of an internal combustion engine. As shown, the novel coupling unit of the invention is associated with the shaft of a magneto or the like for the purpose of automatically varying the timing of the sparks in an ignition system relative to the positions of the pistons in the engine in which the sparks occur. The coupling unit is employed for connecting a rotating part of an engine (not shown) to the rotor shaft 5 in a magneto 6 which may be of any suitable design well known in the art and, hence, is only partially shown. In a manner also well understood by those skilled in the art, the rotor of the magneto is drivably connected with a circuit breaker cam (not shown) which operates in timed relation to the rotor and determines the time of the occurrence of the sparks in the engine cylinders. In a structure of this character wherein the timing cam is driven by the magneto rotor, the coupling unit of the present invention is preferably located so that the rotor and the cam are affected alike by adjustments made by said unit, thereby insuring the opening of the primary circuit of the magneto coil at the most advantageous moment for efficient operation irrespective of the adjustments effected by the coupling unit.

As herein shown, the novel coupling means whereby shaft 5 is flexibly connected to an engine driven part for automatic angular adjustment relative thereto, comprises a spur pinion 7 (Figs. 1 and 3) which may be considered as the driv-

55

ing member of the coupling unit since it is connected, although not necessarily, to the prime mover, which in the present instance is a rotating part of an engine on which magneto 6 is mounted. For this purpose, the hub portion 3 of pinion or driving member 7 is provided at one end thereof with external splines 9 that are adapted to engage an internally splined rotating part of the engine. Pinion 7 is provided with a bearing sleeve or bushing 10 which is loosely mounted on a smooth reduced portion of shaft 5 and projects inwardly beyond said pinion for purposes to be presently described.

Journalled on the projecting end of bushing 10 for free angular movement relative thereto, is a torque transmitting intermediate member in the form of an irregularly shaped plate 11 having hub portions 12 and 13 (Fig. 1) on opposite sides thereof to provide a substantial bearing for said plate, said hub portion 12 telescoping into driving member or pinion 7 to enable positioning of the latter relatively close to plate 11. The holes 14 in plate 11 indicate removal of material from the latter in order to reduce the weight thereof.

Novel centrifugally responsive means are provided for drivably connecting members 7 and 11, and for effecting relative angular movement of said members at a predetermined speed of rotation thereof. As shown, said centrifugally responsive means comprises a pair of gear segments 15, 15 (Figs 1 and 3) disposed diametrically opposite each other and arranged to mesh with the teeth of pinion or driving member 7. Each segment 15 is formed with a horizontal arm portion 16, and with a vertical arm portion 17, the latter arm portion being weighted at its free end as indicated at 18. As shown, each centrifugally responsive weight member 15 is of a thickness throughout substantially equal to the width of the face of pinion 7, and is formed from a single piece of material. It will be understood that the members 15, 15 may be fabricated from a plurality of thin plates or laminations secured together in a suitable manner.

Centrifugal members 15, 15 are pivotally mounted on corresponding ends of sleeves 19, 19 (Fig. 1) which are secured, as by pins 20, 20, in intermediate plate member 11 and project beyond each side of the latter. Screws 21, 21 threaded into sleeves 19, 19 hold centrifugal members 15, 15 against outward endwise displacement on said sleeves. As illustrated in Fig. 3, the weighted arm portions 17, 17 of centrifugal members 15, 15 extend upwardly and downwardly, respectively, at opposite sides of the axis of rotation of shaft 5, and the pivotal arrangement of said centrifugal members is such that each tends to pivot in a counter-clockwise direction (as viewed in Fig. 3) under the influence of centrifugal force upon rotation of members 7 and 11 in the same direction.

Secured in and projecting laterally beyond each side of plate 11 are pins 22, 22 (Figs. 3 and 4) corresponding ends of which are normally engaged by the arm portions 16, 16 of centrifugal members 15, 15 to limit rotation of the latter in a clockwise direction (Fig. 3) upon counter-clockwise rotation of pinion 7 and, hence, cause said members and said plate to rotate with said pinion. Pins 22, 22 determine the normal illustrated positions of centrifugal members 15, 15, and also operate to limit the extent of rotation of said members in a counter-clockwise direction under the influence of centrifugal force through

engagement with abutments 23, 23 on said members.

Centrifugal members 15, 15 and plate 11 are normally held in the positions illustrated, with arm portions 16, 16 of said members engaging pins 22, 22, by suitable resilient means, such as a pair of pull or tension springs 24, 24 (Fig. 3). The latter are of like predetermined tension and have corresponding ends thereof connected by means of suitable adapters 25, 25 to corresponding ends of pins 26, 26 which are secured in and project laterally beyond each side of plate 11. Suitable spacer collars 27, 27 surround pins 26, 26. The opposite ends of springs 24, 24 are connected to suitable adapters 28, 28 which extend into the bifurcated ends of studs 29, 29 and are connected thereto by pins 30, 30 that extend through said studs and said adapters. Studs 29, 29 are adjustably threaded in suitable threaded openings in the arm portions 16, 16 of centrifugal members 15, 15. It will thus appear that by rotating the studs 29, 29 the tension of springs 24, 24 may be varied to control the pivotal movement of centrifugal members 15, 15 by centrifugal force at desired speeds. Adjustment of studs 29, 29 as above described is effected after springs 24, 24 are disconnected therefrom.

When the above described parts are rotated in a counter-clockwise direction, as viewed in Fig. 3, at or above a predetermined angular speed, the centrifugal force acting on the weighted ends of centrifugal members 15, 15 causes the latter to pivot counter-clockwise about pivots 19, 19, against the efforts of springs 24, 24, until abutments 23, 23 on said members engage pins 22, 22. This latter movement of centrifugal members 15, 15 causes said members to roll bodily in a counter-clockwise direction about pinion 7 a predetermined angular distance and, hence, effect a predetermined angular movement of intermediate plate member 11 in the same direction relative to pinion or driving member 7. Since member 11 is connected, in a manner to appear hereafter, to the magneto rotor, the latter is moved ahead with respect to the engine driving member 7 when centrifugal members 15, 15 move outwardly and causes an advance in the timing of the sparks in the engine cylinders relative to the positions of the pistons in said cylinders.

Engaged over rotor shaft 5 and disposed at the side of intermediate plate member 11 opposite that at which driving pinion 7 and centrifugal members 15, 15 are arranged is a spur pinion 31 (Figs. 1 and 2) which may be conveniently referred to as the driven member of the coupling unit. Pinion 31 is telescoped over the hub 13 of plate 11 to enable positioning of the same relatively close to said plate, and is drivably connected to rotor shaft 5 by means of splines 32 within the hub 33 of said pinion that mesh with external splines 34 on said shaft.

Novel centrifugally responsive means are provided for drivably connecting intermediate plate member 11 to pinion or driven member 31, said means being similar to but having different operating characteristics than the connecting means 15, 15 between members 7 and 11. As shown, the connecting means for members 11 and 31 comprises a pair of gear segments 35, 35 (Figs. 1 and 2) disposed diametrically opposite each other and arranged to mesh with the teeth of pinion 31. Each segment 35 is formed with a horizontal arm portion 36, and with a vertical arm portion 37, the latter arm portion being

weighted at its free end as indicated at 38. As shown in Fig. 4, the arm portions 36 and 37, and the weight portions 38 of the centrifugal members 35, 35 are thinner than the arm portions 16 and 17 and the weight portions 18 of centrifugal members 15, 15. Thus, centrifugal members 35, 35 are lighter in weight than the centrifugal members 15, 15. The centrifugal members 35, 35 are formed, in the illustrated embodiment, from a single piece of material, but may be fabricated from a plurality of thin plates or laminations if desired.

The centrifugal members 35, 35 are arranged the same as and in axial alignment with centrifugal members 15, 15, to pivot outwardly in the same direction as the latter under the influence of centrifugal forces acting thereon. Accordingly, the centrifugal members 35, 35 are pivotally mounted on the ends of sleeves 19, 19 that project beyond the sides of plate 11 adjacent driven member or pinion 31. Screws 39, 39 are threaded into said ends of sleeves 19, 19 hold centrifugal members 35, 35 against inward end-wise displacement on said sleeves.

Pivots connected at 40, 40 to the arm portions 36, 36 of centrifugal members 35, 35 are bifurcated blocks 41, 41 each having adjustably threaded therein a suitable spring connector or adapter 42. Connected with adapters 42, 42 are corresponding ends of pull springs 43, 43 which are of like predetermined tension but preferably somewhat greater than the predetermined tension of springs 24, 24 for centrifugal members 15, 15. The opposite ends of springs 43, 43 are connected to suitable adapters 44, 44, which, in turn, are connected to the projecting free ends of pins 26, 26. Suitable spacer collars 45, 45 surround pins 26, 26 between adapters 44, 44 and the adjacent side of plate 11. The arm portions 36, 36 of centrifugal members 35, 35 are normally held in engagement with the projecting free ends of pins 22, 22 by springs 43, 43 which determine the normal illustrated position of said members and prevent rotation of the latter beyond said position by said springs. Pins 22, 22 also operate to limit the extent of outward movement of centrifugal members 35, 35 under the influence of centrifugal force through engagement of abutments 46, 46 on said members with said pins. Springs 43, 43 in resisting the outward movement of centrifugal members 35, 35 cause said members to transmit the rotation of plate 11 and the above described angular movement of the latter relative to driving pinion 7 to driven member or pinion 31 and rotor shaft 5. The tension of springs 43, 43 may be varied to control the outward movement of centrifugal members 35, 35 by centrifugal force at desired speeds by adjusting the adapters 42, 42, which is effected after said springs are disconnected from pins 26, 26.

The parts of the coupling unit are held in assembled relation by a nut 47 which is threaded onto the end of rotor shaft 5. In order to insure free angular movement of members 7 and 11 relative to each other and to shaft 5, a washer or ring 48 is disposed between spacer sleeve 10, plate 11 and member 31. Sleeve 10 is slightly longer than the combined lengths of the hubs of members 7 and 11 and the outer end thereof is engaged by a washer 47 to limit axial movement of member 7.

When the driving and driven parts 7 and 31 are rotated in a clockwise direction, as viewed in Fig. 2, at a predetermined speed, which is higher than that required to cause centrifugal members

15, 15 to move outwardly, in the manner described above, the centrifugal force acting on the weighted ends of centrifugal members 35, 35 causes the latter to pivot clockwise (as viewed in Fig. 2) about pivots 19, 19, against the tension of springs 43, 43, until abutments 46, 46 on said members engage pins 22, 22. Since during this functioning of centrifugal members 35, 35 there is no relative angular movement of members 7 and 11, the driven member or pinion 31 and rotor shaft 5 are rotated in a counter-clockwise direction (Fig. 2) relative to driving member 7 and plate 11 a predetermined angular distance, thereby causing a retardation of the sparks in the ignition system served by magneto 6. It will be noted that the views of Figs. 2 and 3 are taken in different directions as respects Fig. 1. As the angular speed of the parts is reduced to or slightly below the predetermined speeds at which centrifugal members 15, 15 and 35, 35 reach the outward limits of their movements, in the manner above described, springs 24, 24 and 43, 43, respectively, return said centrifugal members to their normal illustrated positions, thereby reversing the relative angular movements of the parts and, hence, the advance or retardation of the spark caused by the outward movements of said centrifugal members. Thus, an engine may, for example, be operated at one spark setting for low speeds, at an advanced spark setting for intermediate speeds, and at a retarded spark setting for high speeds, said spark settings being automatically effected by the apparatus of the present invention.

It will be understood that by properly designing the parts above described a variety of modes of operation may be obtained. If the relative angular positions of members 7, 11 and 31 or, in the illustrated structure, spark advance and retard is plotted against the angular speed of member 7, the contour of the curve obtained may be greatly varied, for example, by changing the initial tension or design of springs 24 and 43, by adjusting the spring contours 29 and 42, by varying the extent of outward movement of centrifugal members 15, 15 and 35, 35, or by varying the characteristics of the centrifugal weight members.

There is thus provided novel coupling means for rotatable parts, such as a magneto or timer rotor and drive shaft therefor, whereby relative angular movements of said parts in either direction may be automatically effected during rotation thereof, and whereby relative angular movements in opposite directions may be effected as the speed of rotation increases. Additionally, said coupling means includes means, as in the centrifugal members 15 and 35, so constructed as to effect different relative angular movements of the connected parts at predetermined speeds thereof in response to centrifugal forces. The coupling units provided may be employed in a novel manner to automatically control the spark setting of an ignition system in an infinite variety of ways for the purpose of obtaining efficient and economical operation at substantially all speeds. Furthermore, the novel coupling means provided are simple in construction and operation and are also compact and reliable.

Although only one embodiment of the invention is illustrated and described in detail, it is to be expressly understood that the same is not limited thereto. As will now be apparent to those skilled in the art, various changes, such as in the design and arrangement of the parts illustrated,

may be made in the illustrated embodiment of the invention without departing from the spirit and scope thereof. For example, only one of each of the centrifugal members 15 and 35 may be effectively employed and disposed at opposite sides of plate 11 and diametrically opposite each other. For a definition of the limits of the invention, reference is had primarily to the appended claims.

What is claimed is:

1. In apparatus of the class described, a rotatable driving member, a driven member mounted for rotation with and angular movement relative to said driving member, and means for drivably connecting said members comprising an intermediate connecting member and centrifugally responsive means pivotally mounted on said intermediate member and having direct gear teeth engagement with said driving and driven members, said responsive means comprising centrifugal weights of different sizes extending from their respective pivotal axes in a common circumferential direction relative to the axis of rotation of said driving and driven members so as to be operable to effect relative angular movement of said members in different directions at different increasing speeds of rotation in response to centrifugal forces acting on said responsive means.

2. Apparatus of the class described comprising two rotatable members adapted for angular movement relative to each other, means for transmitting a driving torque from one of said members to the other comprising centrifugally responsive means including a pivoted centrifugal weight directly engaged with each of said rotatable members, said weights being of different mass and mounted to extend from their respective pivotal axes in the same circumferential direction with respect to the axis of rotation of said rotatable members so as to be operable to first effect relative angular movement of said members in one direction and then effect relative angular movement of said members in the other direction at different speeds as the speed of rotation of said members increases, and resilient means for controlling the movement of said responsive means in response to centrifugal forces.

3. In apparatus of the class described, a driving pinion, a driven pinion axially spaced from said driving pinion, and means drivably connecting said pinions whereby the latter rotate together and are adapted for limited angular movement relative to each other, said connecting means comprising a plate member disposed between said driving and driven pinions, a first centrifugally responsive gear segment pivotally mounted on said plate member and meshing with said driving pinion, and a second centrifugally responsive gear segment pivotally mounted on said plate member and meshing with said driven pinion, said first and second gear segments being adapted to become operative under the influence of centrifugal force at different speeds of rotation of said driving and driven pinions to effect a limited relative angular movement of said driving and driven pinions first in one direction and then in the opposite direction.

4. Apparatus of the class described comprising a toothed driving member, a toothed driven member axially spaced from said driving member, means drivably connecting said members whereby the latter rotate together and are adapted for limited angular movement relative to each other, said connecting means comprising a plate member disposed between said driving and driven

members, a first centrifugally responsive toothed segment pivotally mounted on said plate member and meshing with the teeth of said driving member, a second centrifugally responsive toothed segment pivotally mounted on said plate member and meshing with the teeth of said driven member, said first and second segments being adapted to become operative under the influence of centrifugal force at different speeds of rotation of said driving and driven members to effect a limited relative angular movement of said driving and driven members first in one direction and then in the opposite direction, and resilient means for controlling the movements of both of said segments in response to centrifugal forces.

5. In apparatus of the class described, a driving pinion, a driven pinion axially spaced from said driving pinion, means drivably connecting said pinions whereby the latter rotate together and are adapted for limited angular movement relative to each other, said connecting means comprising a plate member disposed between said driving and driven pinions, a first centrifugally responsive gear segment pivotally mounted on said plate member and meshing with said driving pinion, a second centrifugally responsive gear segment pivotally mounted on said plate member and meshing with said driven pinion, said first and second gear segments being adapted to become operative under the influence of centrifugal force at different speeds of rotation of said driving and driven pinions to effect a limited relative angular movement of said driving and driven pinions first in one direction and then in the opposite direction, a spring for controlling the movement of said first gear segment in response to centrifugal force, means for connecting said spring with said first gear segment and with said plate and providing for adjustment of said spring to vary the tension thereof, a spring for controlling the movement of said second gear segment in response to centrifugal force, and means connecting said last-named spring with said plate and with said second gear segment and providing for adjustment of said spring to vary the tension thereof.

6. Apparatus of the class described comprising a driving pinion, a driven pinion arranged coaxially with and spaced from said driving pinion, and means drivably connecting said pinions comprising a plate member rotatably mounted between said driving and driven pinions, a first pair of circumferentially spaced gear segments pivotally mounted on said plate member and meshing with said driving pinion, and a second pair of circumferentially spaced gear segments pivotally mounted on said plate member and meshing with said driven pinion, said first and second pairs of gear segments being adapted to become operative under the influence of centrifugal force at different speeds of rotation of said driving and driven pinions whereby a limited relative angular movement of said driving and driven pinions is effected first in one direction at one speed of rotation and then in the opposite direction at another speed of rotation.

7. In apparatus of the class described, a driving pinion, a driven pinion arranged coaxially with and spaced from said driving pinion, and means drivably connecting said pinions comprising a plate member rotatably mounted between said driving and driven pinions, a first pair of circumferentially spaced gear segments pivotally mounted on said plate member and meshing with said driving pinion, and a second pair of cir-

cumferentially spaced gear segments pivotally mounted on said plate member and meshing with said driven pinion, said first and second pairs of gear segments being adapted to become operative under the influence of centrifugal force at different speeds of rotation of said driving and driven pinions whereby a limited relative angular movement of said driving and driven pinions is effected first in one direction at one speed of rotation and then in the opposite direction at another speed of rotation, and resilient means resisting movement of each pair of said centrifugally responsive gear segments in response to centrifugal forces.

8. Apparatus of the class described comprising a rotatable driving member, a rotatable driven member, means drivably connecting said members whereby the latter rotate together and are adapted for limited angular movement relative to each other, said connecting means comprising an intermediate member, means centrifugally responsive to one speed including a pivotally mounted centrifugal weight on said intermediate member and directly engaged with said driving member, other means centrifugally responsive to another speed including a pivotally mounted centrifugal weight of different mass than said first named weight on said intermediate member and directly engaged with said driven member, one of said centrifugally responsive weights being so mounted and engaged with said driving member to effect relative angular movement of said rotatable members in one direction in response to centrifugal forces at one speed and the other of said centrifugally responsive weights being so mounted and engaged with said driving member to effect relative angular movement of said rotatable members in the other direction in response to centrifugal forces at a different speed, said weights having the free ends thereof extending from their respective pivotal axes in a common circumferential direction relative to the axis of rotation of said members, and resilient means centripetally loading both of said centrifugally responsive means.

responsive means.

9. Apparatus of the class described comprising a toothed driving member, a toothed driven member, and means drivably connecting said members whereby the latter rotate together and are adapted for angular movement relative to each other, said connecting means comprising a support and oppositely impelled centrifugally responsive toothed segments pivotally mounted on said support, one of said segments meshing only with the teeth of said driving member and the other of said segments meshing only with the teeth of said driven member, said segments being

of different masses and having the free ends thereof extending from their respective pivotal axes in a common circumferential direction relative to the axis of rotation of said members to effect relative angular movement of said members in different directions at different speeds.

10. A coupling including relatively rotatable aligned shafts, gears on the shafts, a support between the gears rotatable with respect to the shafts, centrifugal levers pivotally mounted on the support with the free ends containing the centers of mass thereof extending from their respective mounting pivots in a common circumferential direction with respect to the axis of rotation of the shafts, and having gear segments on the other ends of the levers meshing with the gears.

11. A coupling including relatively rotatable aligned shafts, gears on the shafts, a support between the gears rotatable with respect to the shafts, centrifugal levers pivotally mounted on the support, gear segments on the levers meshing with the gears, said levers being of substantially different inertia and extending from their respective pivotal axes in a common circumferential direction relative to the axis of rotation of the shafts, and resilient means centripetally loading said centrifugal levers.

12. A coupling including relatively rotatable aligned shafts, gears on the shafts, a support between the gears rotatable with respect to the shafts, centrifugal levers pivotally mounted on the support, gear segments on the levers meshing with the gears, said levers being of substantially different inertia and pivoted for centrifugal motion with the free ends containing the centers of mass thereof extending from their respective pivotal axes in the same circumferential direction relative to the axis of rotation of the shafts for imparting opposite relative angular movements to said shafts at different speeds of rotation thereof, and resilient means centripetally loading said centrifugal levers.
